UNITED STATES PATENT OFFICE.

CHARLES HALL DAVIS, OF PETERSBURG, VIRGINIA.

INTEREST-BEARING INSTRUMENT OF OBLIGATION.

No. 835,703.

Specification of Letters Patent.

Patented Nov. 13, 1906.

Application filed February 19, 1906. Serial No. 301,919.

To all whom it may concern:

Be it known that I, CHARLES HALL DAVIS, a citizen of the United States, residing at Petersburg, in the county of Dinwiddie and 5 State of Virginia, have invented certain new and useful Improvements in Interest-Bearing Instruments of Obligation, of which the following is a specification.

My invention relates to improvements in 10 interest-bearing instruments of obligation, such as bonds, certificates of deposit, and the like.

Heretofore interest-bearing bonds have 15 been provided with interest - coupons connected therewith; but such bonds and coupons have been of very circumscribed utility—practically useful only where a large number of bonds of like face value and bearing like interest are to be issued. It has been the practice 20 in such prior constructions to engrave the bonds and the interest-coupons with the face value of the former and the interest value of the latter. This prior practice is altogether unsuited to the issuance of interest-bearing bonds, certificates of deposit, or the 25 like, of miscellaneous and ever-varying face value, and in respect of which the accruing interest is correspondingly miscellaneous or ever varying. In respect of such miscellaneous 30 face-value instruments there has been no way prior to my invention of providing them with appropriate interest - coupons, which may be negotiated as such and which when paid by the obligor serve as a receipt 35 for the interest payment. On the contrary, without my invention a complicated system of books relating to the interest payments of such instruments would be necessary, but which is done away with according to said invention.

My invention has for its object the provision of a new construction of interest-bearing bond, certificate of deposit, or like instrument of obligation, provided with interest-coupons 45 and of extreme flexibility of adaptation to miscellaneous face or principal value and rate of interest.

With this object in view the invention consists in an instrument of obligation having 50 the features hereinafter described. That which is regarded as new will be set forth in the clauses of claim appended to the description.

In the accompanying drawings, illustrating 55 the best-known embodiment of my invention and in which, for example, is illustrated a cer-

60 tificate of deposit bearing interest at 4 per centum per annum, payable quarterly, Figure 1 is a face view of the body of the certificate; Fig. 2, a similar view of the interest-coupons covering a period of one year; Fig. 3, a perspective of the certificate and interest-coupons in book form; Fig. 4, a rear view of one of the coupons.

In said drawings the reference-numeral 1 65 designates the body of the certificate, which in practice is in blank form. It has a space 1^a to receive the name of the obligor, which space for convenience of illustration is in the drawing filled in with the name of a fictitious company. It also has a suitably-designated space 1^b for the name of the obligee, which for convenience of illustration is filled in with the fictitious name of "Joe Roe," and a suitably-designed space 1^c, in which is to be written the amount of the principal of the 70 obligation and which for convenience of illustration is in the drawings filled in with the arbitrary amount "Five hundred and seventy-three." Spaces 1^d 1^e are also provided for 75 the signature of the obligor or the officers thereof, if the obligor be a corporation. Other suitable spaces for the date of issue of the obligation and the amount of the interest it is to bear are provided. These spaces, except 80 as made material in the following clauses of claim, may be varied or omitted and the form of the body of the instrument altered, as circumstances may require. Finally, it is provided with a suitably-designed space 1^f 85 90 to receive an identifying-legend, such as a number, which is arbitrarily shown in the drawings as 13. Associated therewith may be a stub 2, to be retained as a record of the obligor, bearing suitable indicia identifying 95 the certificate issued and the party to whom issued and other desired information.

Combined with the certificate, being secured thereto by staples 3, in the illustrated, though not exclusive, example of the invention, are interest-coupons 4, covering the contemplated or possible life of the certificate, which may be arranged in sheets appropriated to desired divisions of time, couponsheets appropriated to one year and comprising four quarterly coupons being shown in the drawings as one convenient arrangement, and a sufficient number of such yearly coupon-sheets are employed, preferably in superposed relation, to cover the contemplated 105 or probable life of the security—say ten, twenty, or more years.

- Each of the coupons is provided with a series of columns of numerals "5" of decimal value, one column being applied to cents, another to dimes, another to dollars, and so on, as many columns being employed as desired, and associated with such columns-numerals "6" designating the maximum interest payable in any transaction within the scope of the general business contemplated.
- For convenience the nature and intended use of the series of columns of numerals may be indicated by the indicia "Cents," "Dimes," "Dollars," &c., and the words "Value of this coupon" or the like. By means of numerals duplicated on each coupon the bond, certificate of deposit, or the like, and the interest-coupons combined therewith are extremely flexible. The former may be issued for any amount desired within the scope of the general maximum transaction designed, the interest accruing at the several periods when it is designed that interest shall be payable calculated, and the amount of such interest indicated on each coupon in the columns of numerals described by punching out the proper numerals in the several columns or otherwise, as may be desired. The several coupons will then show on their face the money value thereof and may be negotiated accordingly.
- Each coupon is provided with suitably designated spaces 2^a , 2^b , and 2^c to receive, respectively, the date of its maturity, an identifying number or legend to accord with the identifying number or legend on the body portion 1 and the date of issue of the certificate or other instrument of obligation to which it relates, which date of issue may be written or cut in the coupon and restrictions may be set out thereon—such, for instance, as those appearing on the back of each coupon. (Shown in Fig. 4.) Furthermore, if desired, and this is regarded as a valuable auxiliary feature, the coupons may be provided with columns of numerals "7," similar in arrangement to those described and designated as "5," except of arbitrarily higher value and intended to be used to indicate or designate the face value of the bond or like instrument to which the coupon relates. As shown, the several columns of figures "7" are appropriated to unit, ten, and hundred dollars and may be extended to higher value, if desired. The purpose of these columns of numerals may be indicated by the words "Face value of certificate" associated therewith or words of a like import. In said columns of numerals, by punching or otherwise, the face or principal value may be indicated. The provision of this set of numerals "7" serves as a counter-check to the designation of the interest value of the coupon indicated in the columns 5, constituting a double guard against fraudulent alteration in the designation of the value of the coupon, and this protection may be further increased by the restriction 65

appearing on the back of the coupon, the exact phraseology of which restriction will of course be made to suit the percentage value of the coupon.

In the illustrative example of invention 70 shown the certificate of deposit is made out for five hundred and seventy-three dollars, bearing interest at four per cent. per annum in four quarterly payments, the face value being written in the body of the certificate 75 and punched out in the column of figures "7." The interest payable quarterly on this certificate is one per cent. of the face value thereof, and accordingly this has been indicated by punching out the amount "\$5.73" 80 in the columns of figures "5."

When the contemplated life of the certificate covers a period of years, the arrangement of coupons shown, four on a sheet, each sheet covering a year, and the sheets being in 85 superposed relation, is a very convenient arrangement thereof to facilitate the quick issuance of the certificate and the designation on the coupons of the face value thereof and the interest value of each coupon, as 90 thereby the columns of figures "5" and "7" on each sheet will be in register on the coupons of the several sheets and may be simultaneously punched.

It will be apparent, of course, that if a certificate is issued at such time that the maturity date of the first coupon will be less than a full quarter or other arbitrary interest-paying date, so that it will not be entitled to have full value, the interest value of this 100 coupon will be calculated and designated in the column of figures separately and apart from the other coupons.

Having thus described my invention, what I claim is—

1. An interest-bearing instrument of obligation, consisting of a blank body portion having a suitably-designated space in which the amount of the face value of the obligation may be arranged, and a plurality of interest-coupons, said coupons each provided with suitably-designated like columns of numerals in which may be indicated the money value of the coupon at maturity.

2. An interest-bearing instrument of obligation consisting of a blank body portion having a suitably-designated space in which may be arranged the amount of the face value of the obligation and a suitably-arranged space to receive an identifying-legend, 115 and a plurality of interest-coupons, said coupons each provided with suitably-designated like columns of numerals in which may be indicated the money value of the coupon at maturity, and also with suitably-designated 120 spaces to receive an identifying-legend corresponding to that of the body portion.

3. An interest-bearing instrument of obligation consisting of a blank body portion having a suitably-designated space in which 130

- may be arranged the amount of the face value of the obligation, and a suitably-designated space to receive an identifying-legend, and a plurality of interest-coupon sheets, each sheet containing a plurality of coupons, the several coupon-sheets being arranged in superposed relation, and each coupon provided with suitably-designated like columns of numerals in which may be indicated the money value of the coupon at maturity, and also with a suitably-designated space to receive an identifying-legend corresponding to that of the body portion.
4. An interest-bearing instrument of obligation consisting of a blank body portion having a suitably-designated space in which may be arranged the amount of the face value of the obligation, and a plurality of interest-coupon sheets, the several coupon-sheets being arranged in superposed relation with the coupons thereof in register, and each coupon having suitably-designated like columns of numerals in which may be indicated the money value of the coupons at maturity, and also with suitably-designated columns of numerals of higher value than the interest-indicating columns of numerals in which may be indicated the face value of the obligation.
5. An interest-bearing instrument of obli-
- gation consisting of a blank body portion having a suitably-designated space in which may be arranged the amount of face value of the obligation, and a plurality of coupons connected therewith, the several coupons being arranged in superposed relation, and each coupon provided with suitably-designated like columns of numerals in which may be indicated the money value of the obligation at maturity.
6. An interest-bearing instrument of obligation consisting of a blank body portion having a suitably-designated space in which may be arranged the amount of the face value of the obligation, and a plurality of interest-coupons, the several coupons being arranged in superposed registering relation, and each coupon provided with suitably-designated like columns of numerals in which may be indicated the money value of the coupons at maturity, and also with columns of numerals of higher value in which may be designated the face value of the obligation.
- In testimony whereof I have hereunto set my hand in the presence of two subscribing witnesses.

CHARLES HALL DAVIS.
